UNITED STATES PATENT OFFICE.

SAMUEL M. WAGAMAN, OF HAGERSTOWN, MARYLAND.

LOOSE-LEAF BINDER.

Application filed April 20, 1921. Serial No. 462,840.

To all whom it may concern:

Be it known that I, SAMUEL M. WAGAMAN, a citizen of the United States, residing at Hagerstown, in the county of Washington and State of Maryland, have invented new and useful Improvements in Loose-Leaf Binders, of which the following is a specification.

This invention relates to a loose leaf binder, and the main object thereof is to provide novel cooperating leaf-holding components having such arrangement and shape that the leaves will be given a convex and concave assemblage contour, respectively, at the back and front edges similar to the fixed bound leaves of ordinary books. A further object of the invention is to provide simple leaf-holding components on which the leaves may be readily applied and positively retained in close or compact arrangement, and from which the leaves may be easily and quickly removed for replacement or readjustment. A further object of the invention is to provide a binder having loose leaf retaining components to and from which the leaves may be applied or removed at both the front and back portions of the binder to permit leaves to be applied or removed relatively to the rear half or section of the group of assembled leaves fully to an intermediate point, without requiring displacement of the front half or section of the leaves. A still further object of the invention is to generally improve loose leaf binders to conveniently facilitate the application and removal of individual leaves, the parts of the binder, and particularly the leaf-retaining components, being strong and durable and having a novel form of fastening means for holding the leaves thereon in assembled relation.

With these and other objects and advantages in view, the invention consists in the preferred construction and arrangement of the several parts which will be more fully hereinafter described and claimed.

In the accompanying drawings forms of the improved loose leaf binder organization are embodied to illustrate a practical assemblage of parts involving the features of the invention, but capable of change in the general proportions and contours as well as in the number of the several components to adapt the latter to various applications.

In the drawings:

Fig. 1 is a perspective view of a portion of a binder, showing one of the backs open and embodying the features of the invention.

Fig. 2 is a section on the line 2—2, Fig. 1.

Fig. 3 is a section on the line 3—3, Fig. 1.

Fig. 4 is a perspective view of a portion of the binder, showing parts thereof released.

Fig. 5 is a section on the line 5—5, Fig. 1.

Figs. 6 and 7 are detail perspective views of the leaf-engaging posts and securing components therefor.

Fig. 8 is a perspective view of a portion of the binder, showing a modification in the construction of a part of the components.

Fig. 9 is a view similar to Fig. 5, showing a further modification, and whereby the leaves may be applied and removed at both the front and back portions of the binder.

Fig. 10 is a transverse vertical section on the line 10—10, Fig. 9.

Fig. 11 is a transverse vertical section on the line 11—11, Fig. 9.

The numerals 5 and 6 respectively represent the covers of the binder connected by a flexible back 7, the covers 5 and 6 adjacent to the flexible back 7 having attaching strips 8 and 9 secured thereto and formed with inwardly projecting doubled leaf-attaching members 10, one on each, which are continuous with a curved back support 11 which is free of the flexible back 7 and engaged by the group 12 of loose leaves when the latter are assembled in the binder, as shown in the drawings and particularly by Figs. 1, 2 and 3. The leaf-attaching member 10 of the strip 8 is provided with perforations 13 located near the opposite ends of said member to coincide with the outermost openings 14 through the loose leaves and through front and rear fly leaves 15. The openings 14 through the loose leaves 12 and fly leaves 15 are adapted to receive fixed retaining posts 16 which are passed therethrough, said posts being secured at their rear ends, in the form of the binder shown in Figs. 1 to 8, inclusive, to a bar or metal strip 17 inserted in the rear attaching strip 10, as clearly shown in Fig. 5. The leaf-retaining posts 16 are notched, as at 18, adjacent their free ends, which notches are engaged by an elongated spring locking strip 19 of the form shown in detail in Fig.

95

100

105

110

6, the spring locking strip 19 having elongated openings adjacent its ends, of which openings the end walls nearest the ends of the strip 19 are preferably curved, as at 22, 5 and the opposite end walls are preferably straight, as at 21. However, said end walls may be of any other shape which is adapted for the same purpose. The spring strip 19 is of a thickness slightly less than the 10 width of the notches 18, so that the straight walls 21 at the inner ends of the openings 20 may enter the notches 18 and the spring locking strip 19 be thereby retained in engagement with the ends of the posts 16, 15 particularly in view of the spring tension 18 exerted by said strip 19. The strip 19 is reversible and may be disengaged from the notches 18 of the posts 16 by flexing the strip 19 at the center. This locking strip 20 25 constitutes a very simple form of positive locking means, and, when this strip is to be applied, the leaf-attaching member 10 projecting from the front cover 5 is brought over, so that the openings 13 there-in will receive the adjacent ends of the posts 16. The notched ends of the posts 16 are caused to project through the front attaching strip 10 far enough to expose the notches, and the spring locking strip 19 is 30 then applied, as shown in Fig. 1, to firmly and positively hold the loose leaves 12 between the covers 5 and 6. It will be understood that in the form of the binder shown in Figs. 1 to 8, inclusive, the loose leaves 12 35 are all applied over the posts 16, and when a predetermined number of the loose leaves have been applied to the posts 16, the locking strip 19 is fitted to the slots 18 of the posts 16. The locking strip 19 may be readily removed by drawing the center thereof outwardly, and thereby moving the opposite extremities of the said strip longitudinally toward one another a sufficient distance to release the transversely straight 40 walls 21 of the openings 20 in the locking strip 19 from the notches 18. When the locking strip 19 is detached, the leaf-attaching member 10 is disengaged from the ends of the posts 16, and, likewise, the fly leaves 45 50 55 and any number of the loose leaves 12 may then be withdrawn from, or other similar leaves applied on, the posts 16, if the full capacity of the binder has not been reached.

55 The improved binder also includes intermediate transfer posts 23, which extend through the front fly leaf 15 and are secured thereto either by rectangular washer strips 24 individually applied to the ends 60 of these transfer posts, as shown in Fig. 7, or by circular washers 25, shown in Fig. 8, the ends of the posts 23 being swaged upon the washers 24 or 25. The ends of the posts 23 opposite those engaged by the washers 24 or 25 are free and inserted through open-

ings 26 of all of the loose leaves 12 in the form of the binder shown in Figs. 1 to 8, inclusive. When the spring locking strip 19 is detached from the posts 16, all of the leaves may be removed from the latter without disengaging the posts 23 from said leaves, and by this means all of the leaves may be held assembled in the full group thereof. When the leaves 12 are applied to the posts 16 and have the posts 23 extending therethrough, as shown by Fig. 5, the said posts 23 operate to reinforce rear edges of the leaves intermediate their ends and to preserve the group of associated or assembled leaves in the desired assemblage. 80

In the modified form of the device as shown in Figs. 9, 10 and 11 the retaining posts 16^a have both the front and rear ends thereof formed with notches 18 and 18^a, respectively, and arranged for engagement, 85 respectively, by a locking strip 19 and a similar strip 19^a, both locking strips 19 and 19^a in this modified structure operating in the same manner as the strip 19 heretofore described. In the modified structure the transfer posts 23^a are shown as intermediately divided to form sections 27 and 28 secured, respectively, at their outer ends by washers 24, similar to those heretofore described, against the fly leaves 15. The inner end of each post section 27 is preferably formed with a conical recess 29 and the corresponding end of the section 28 is conically tapered, as at 30, to snugly and closely fit in the said recess, to form a flush joint 100 between the two inner ends of the sections to facilitate insertion and withdrawal of the post sections 27 and 28 when desired, these post sections extending through intermediate openings 26 in the loose leaves 105 12 in the same positions as shown in Fig. 5.

The transfer posts 23 and the modified form thereof comprising the sections 27 and 28 are curved similarly to the retaining posts 16, all of the posts having a convex 110 trend towards the flexible back 7 which connects the covers 5 and 6 and the concave sides towards the front or free edges of the leaves. By curving all of the posts as specified, the rear convex and front concave association of the edges of the leaves is obtained and preserved by reason of the rigidity of the posts. The curvature of the posts is also of material advantage when 115 opening and closing the loose leaves of the binder as a whole in preventing tearing strain on the attached or post-engaged rear edge portions of the loose leaves, and, moreover, the curved posts cause the loose leaves, 120 when the binder is opened, to assume proper relative positions. By forming the intermediate transfer posts in sections, as shown by Figs. 9 and 11, and having the retaining posts 16 engaged at opposite ends by locking strips of a similar character for releas- 125 130

ing either set of ends of said retaining posts, the loose leaves may be removed from and applied to the several posts either at the front or the rear half portions of the binder, 5 thereby avoiding the necessity of entirely removing the front half of the full group of assembled leaves when it is desired to apply a leaf in connection with the rear half of the group of leaves. This avoids 10 disturbing or disorganizing the entire group of associated leaves when it is desired to insert an additional loose leaf or substitute a loose leaf for another previously temporarily bound by the improved device.

15 This makes it possible to easily introduce leaves bearing modified or corrected matter relating to the same or relative subjects at the proper place in the group of leaves.

The front and rear fly leaves, to one of 20 which the transfer posts 23 shown in the form of the invention disclosed by Figs. 1 to 8, inclusive, are attached, and to which the sections 27 and 28 of the divided transfer post 23^a shown in Figs. 9 to 11, inclusive, are, respectively, secured, may be of any preferred stock and are free of the covers 5 and 6 and the strips 10, and said fly leaves may be of any suitable thickness or material adapted for the purpose. It 25 has been found that heavy paper stock practically answers the purpose of these fly leaves, yet at times it may be desirable to use a fabric or composite form of fly leaf having sufficient body to hold and oper-

30 35 40 45 50 55 60 65 70 75 80 85 90 95 100 105 110 115 120 125 130

atively support the transfer posts in either form shown and hereinbefore described. To give the front attaching strip 10 sufficient rigidity and wearing durability, especially in view of the openings 13 formed therein, it has a metal strip 10^a inserted between the folds thereof and extending throughout a portion of the length of the same, said metal strip 10^a having openings therethrough which registering with the openings 13. In

some instances, however, this metal strip 10^a 45 may be omitted where a stock is used having sufficient thickness and wearing resistance to prevent tearing or fraying of the walls of the openings 13. The strip 10^a is similar in structure and dimensions to the strip 17 to which the posts 16 are shown as secured at their rear ends in Figs. 1 to 8, inclusive.

From the foregoing the operation of the 50 binder will be readily understood. The detachment of the spring locking strip 19, or both of the strips 19 and 19^a, may be readily accomplished to permit placement or withdrawal of the loose leaves, the fly leaves 55 60 65 70 75 80 85 90 95 100 105 110 115 120 125 130

15, either individually or jointly, may be quickly and readily removed from their applied positions, and in the form of the binder shown in Figs. 1 to 8, inclusive, the front fly leaf 15 may be withdrawn and replaced simultaneously with the posts 23.

Similarly, where divided transfer posts such as those shown at 23^a in Figs. 9 to 11, inclusive, are employed, the fly leaves may be simultaneously withdrawn and replaced with the sections 27 and 28 of the latter 70 posts. It will be understood, however, that the user of the binder may use his own judgment as to how the leaves are to be inserted and removed in order to arrive at the result sought with the greatest convenience and to the best advantage, in view of the fact that a number of different courses may be pursued in operating the several parts.

What is claimed as new is:

1. A loose leaf binder having front and rear covers, retaining and transfer posts disposed between the covers and adapted to enter openings in a plurality of leaves, said transfer posts being composed of separable sections to permit a part of said leaves to be removed and be held by a part of said sections with the remaining leaves remaining intact upon said retaining posts and the other post sections, and locking means 80 85 90 95 100 105 110 115 120 125 130

separably engaging the ends of the retaining posts.

2. A loose leaf binder having front and rear covers, rigid curved retaining posts, intermediate curved transfer posts composed of separable parts, the posts being disposed between the covers, and resilient locking means separably engaging the ends of the retaining posts.

3. A loose leaf binder having front and rear covers, rigid retaining posts and intermediate transfer posts between the covers, and resilient locking strips separably engaging the opposite ends of the retaining posts.

4. A loose leaf binder having front and rear covers, rigid curved retaining posts, intermediate rigid curved transfer posts composed of separable sections, the posts being disposed between the covers, and resilient locking strips separably engaging the opposite ends of the retaining posts.

5. A loose leaf binder having front and rear covers with a flexible back connection, attaching strips secured to the covers and in part projecting inwardly from the latter, rigid curved retaining posts associated and cooperating with the attaching strips, rigid curved intermediate transfer posts free of said attaching strips, loose leaves through which the posts are inserted, and locking means separably engaging the ends of the retaining posts.

6. A loose leaf binder having front and rear covers with a flexible back connection, attaching strips secured to the covers and projecting inwardly from the latter, rigid curved retaining posts associated and cooperating with the attaching strips, rigid curved intermediate transfer posts free of

4
said attaching strip, fly leaves free of the said attaching strips with which the intermediate posts are associated, loose leaves between the fly leaves through which the retaining and intermediate posts are inserted, and locking means separably engaging the ends of the retaining posts.

7. A loose leaf binder comprising enclosing covers, retaining and transfer posts to receive a plurality of loose leaves, said transfer posts being composed of complementary sections individually removable at the front and rear of the binder to permit loose leaves to be applied to and removed from said retaining posts at different parts of the assemblage of leaves without disturbing the remainder of said leaves, and means to secure said retaining posts against movement and for removably holding the leaves on the retaining and transfer posts.

8. A loose leaf binder comprising covers and retaining and transfer posts located be-

tween said covers for engagement with a group of loose leaves, each transfer post comprising closely associated separable members, and said retaining posts being provided at their opposite terminals at the front and at the rear of the group of leaves carried thereby with means for holding said group of leaves intact and for permitting a portion of said transfer posts and a portion of said group of leaves carried thereby to be removed from or be applied to the remainder of said group of leaves either at the front or at the back of the complete group of leaves.

In testimony whereof I have hereunto set my hand in presence of two subscribing witnesses.

SAMUEL M. WAGAMAN.
